UNITED STATES PATENT OFFICE.

ALBERT K. MATTHEWS, OF CHICAGO, ILLINOIS.

DESIGN FOR A SOAP HOLDER.

Application filed April 7, 1926. Serial No. 17,202. Term of patent 7 years.

To all whom it may concern:

Be it known that I, ALBERT K. MATTHEWS, a citizen of the United States, residing at Chicago, in the county of Cook and State of Illinois, have invented a new, original, and ornamental Design for a Soap Holder, of which the following is a specification, reference being had to the accompanying drawing, forming part thereof.

I claim:—

The ornamental design for a soap holder, as shown.

ALBERT K. MATTHEWS.
